CLAIM

The ornamental design for a pin, as shown.

DESCRIPTION

FIG. 1 is a perspective view of a pin;

FIG. 2 is a plan view thereof;

FIG. 3 is a left view thereof; and,

FIG. 4 is a right view thereof.

The broken lines shown in FIGS. 1 and 2 depict a symbolic break in the length of the article and form no part of the claimed design.

1 Claim, 2 Drawing Sheets(56)
